A. Peterson Jr., Attorneys,

UNITED STATES PATENT OFFICE.

HEDWORTH HUTCHINSON, OF BURLINGTON, IOWA.

BURIAL-CASKET.

SPECIFICATION forming part of Letters Patent No. 253,708, dated February 14, 1882.

Application filed June 28, 1881. (Model.)

To all whom it may concern:

Be it known that I, HEDWORTH HUTCHINSON, of Burlington, in the county of Des Moines and State of Iowa, have invented certain new and useful Improvements in Burial-Caskets; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view representing one of the corners of my improved burial-casket with its cover. Fig. 2 is a horizontal cross-section through the corner of the body of the casket. Fig. 3 is a top view of a corner of the same with the cover removed. Fig. 4 is a perspective view of the metallic corner of the lid or cover detached; and Fig. 5 is a view of the under side of one of the corners of the cover.

Similar letters of reference indicate corresponding parts in all the figures.

My invention contemplates an improved construction of burial-caskets, as hereinafter more fully set forth, and particularly pointed out in the claim.

In the annexed drawings, A is the body of the casket, the end and side pieces of which are grooved, as shown at *a a*, to receive the side flanges, *b*, of metallic corners B. Each of these corners is cast with bent lugs *c c*, which, when the corner is placed in its proper position, project laterally on the inside of the body A, to which they are secured by screws *d*. I prefer to cast the corners B with open spaces *e* for the display of the trimming C, which is nailed or otherwise secured upon a padded wood backing, D, placed in the corner on the inside or back of the open-work corner-plate B, and held in place at its lower end by a screw inserted through the bottom of the casket and at its upper end by a block of wood, E, (see Fig. 3,) the tongues *f* of which are inserted into the top of the grooves *a a*, a screw,

g, being inserted through the middle of the block down into the backing D.

F is the metallic corner of the cover, which connects the side and end pieces, G G, to which it is secured by the screws *h h*. This corner is cast solid, of the shape clearly shown in the drawings, with a downward-projecting web or flange, F', which, when the cover is placed over the body of the casket, projects down over and protects the wooden corner-block E. 55

H is a wooden corner-brace, which is inserted between the ends of the side and end pieces G G back of the flanged metal corner or corner-plate F.

If desired, the wooden ends of the body A 60 and cover G may be dispensed with by continuing the metallic corner-plates B and F all the way around to the next corner, thus making a combined metallic end and corner-plate of substantially the same construction and application as hereinbefore described. 65

My improvement contributes greatly to the strength and durability of the casket, as well as to the elegance and attractiveness of its appearance, besides saving time and labor in the 70 construction of the casket.

Having thus described my invention, I claim and desire to secure by Letters Patent of the United States—

In a burial-casket, the combination of the 75 sides and ends, having vertical recesses or grooves, the open-work corners B, having end flanges, *b*, and lugs *c*, the padded back or panel D, and the corner-block E, having tongues *f* and screw *g* connecting it to the panel D, which 80 is thereby held in position, substantially as set forth.

In testimony that I claim the foregoing as my own I have hereto affixed my signature in presence of two witnesses.

HEDWORTH HUTCHINSON.

Witnesses:

JOHN TROXEL,
SAMUEL NELSON.
